2,004,430

HEATER FOR LAUNDRY IRONERS

Nicholas L. Etten, Waterloo, Iowa, assignor, by
mesne assignments, to Chamberlain Corpora-
tion, a corporation of Iowa

Application March 8, 1932, Serial No. 597,455

2 Claims. (Cl. 68—9)

At the present laundry ironers are customarily heated with steam, and those intended for domestic use are usually heated electrically because of the dangers attendant upon the use of steam.

5 The object of my invention is to provide a heater for ironers or the like having all of the advantages of the steam heated ironers without the dangers and disadvantages attendant upon the use of steam, and to provide an ironer of this 10 class which may be safely used either as a domestic or commercial ironer.

More specifically it is my object to provide a heater of this class especially designed for use with a liquid whose boiling point is higher than the temperature best suited for ironer heating, so that the iron may be heated in a uniform 15 manner and steadily maintained at the desired temperature without bringing the liquid heating element to the boiling point, and whereby an ordinary gas or oil heater may be employed.

20 My invention consists in the construction, arrangement and combination of the various parts of the device, whereby the objects contemplated are attained, as hereinafter more fully set forth, 25 pointed out in my claims, and illustrated in the accompanying drawing.

The drawing shows a side elevation of an ironing machine of ordinary construction, and illustrates diagrammatically my improved heating 30 apparatus.

Referring to the accompanying drawing, I have used the reference numeral 10 to indicate generally an ironing machine having a heating member 11 of the construction now ordinarily 35 used in connection with steam heated ironing machines. The head 11 is provided with passageways for fluid.

The reference numeral 12 indicates a heater having a coil 13 therein, and a burner 14, which 40 is preferably a gas burner fed by a supply pipe 15. The top of the coil 13 communicates through the pipe 15 with a supply or storage tank 16, and this tank 16 communicates through the pipe 17 with one end of the ironer head; the 45 other end of the ironer head communicates through a pipe 18 with a pump 19 of ordinary construction, and the discharge from the pump flows through a pipe 20 to the bottom of the coil 13.

I have provided a thermostatic valve control 50 device of ordinary construction, indicated generally by the numeral 21 and having a portion thereof 22 projected into the supply tank 16.

This thermostatic control device operates a valve 23 in the gas supply pipe 15 and operates 55 in such a manner that when the temperature of the fluid within the supply tank 16 reaches a certain predetermined height the supply of gas will be cut off, and when the temperature falls below the desired point the valve 23 will be 60 opened.

Contained within the ironer head 11, coil 13, supply tank 16 and all of said pipes is a liquid, the boiling point of which is much higher than that of water. I have successfully employed for this purpose diethylene glycol, the boiling point of which is approximately 450° Fahrenheit.

In an ironing machine it is desirable to have the ironer head heated to a temperature of approximately 390 degrees Fahrenheit, and therefore by the use of this liquid the desired temperature may be maintained in the ironer head without having the liquid approach the boiling point, thereby eliminating all the dangers and objections attendant upon the use of steam for heating laundry heads.

In practical operation when the gas is burning and the pump 19 is being operated, the liquid will flow throughout the entire apparatus, and if it is given a temperature of, say for instance, 390 degrees Fahrenheit in the coil 13, that temperature will be transmitted to and maintained in the ironer head, and the temperature is controlled by the thermostatic regulator governing the gas supply.

In the class of ironers now in general use, 25 which employ steam as the heating medium, it is necessary to make the ironer head strong enough to withstand a pressure of approximately one hundred pounds to the square inch, and as these ironer heads are usually made of cast iron with steam passageways extending through them, it 30 frequently happens that flaws or pockets in the cast iron cause the ironer heads to be broken when steam under pressure is placed therein.

With my device, however, it is not necessary 35 to make the ironer head as heavy or strong, because the liquid flows through it under approximately atmospheric pressure at all times.

I claim as my invention:

1. In an ironing machine, a member to be 40 heated, said member having a fluid passageway therethrough, a heating coil, means for applying heat to the coil, pipes connecting the coil and the member to be heated to form an enclosed system, a liquid filling said member to be heated, 45 the coil and the pipes, said liquid having a boiling point higher than the temperature to which it is desired to heat said member.

2. In an ironing machine, a member to be 50 heated, said member having a fluid passageway therethrough, a container for fluid, means connecting said container and said passageway, a liquid filling said container, connecting means and said passageway, and means independent of 55 said member to be heated for heating said liquid, said liquid having a boiling point higher than the temperature to which it is desired to heat said member.

NICHOLAS L. ETSEN.
